UNITED STATES PATENT OFFICE.

NORRIS ELMORE CLARK, OF PLAINVILLE, CONNECTICUT.

METAL-WORKING.

1,052,888.

Specification of Letters Patent. Patented Feb. 11, 1913.

Application filed October 23, 1912. Serial No. 727,285.

To all whom it may concern:

Be it known that I, NORRIS ELMORE CLARK, a citizen of the United States, and resident of Plainville, in the county of 5 Hartford and State of Connecticut, have invented certain new and useful Improvements in Metal-Working, of which the following is a specification.

This invention relates particularly to a 10 method of forming reticulated metal suitable for instance for concrete reinforcement and metal lath.

My principal object is to provide a simple method which will require relatively inexpensive mechanism for carrying it out and which will produce economically a superior product.

Briefly considered the invention consists in first scoring sections of a sheet of metal 20 in a suitable arrangement leaving parallel unscored margins and also, if desired, intermediate strips. The scoring may be effected by slitting, punching or indenting the sheet in staggered arrangement so that 25 the scored section is extensible in a direction at right angles to its length. Each scored section is made up of two scored portions, the score marks of the two portions of a section being arranged diagonally relative to the length of the sheet and so as to converge forwardly toward a point midway between the edges of the section. The sheet is then subjected to the action of corrugating dies or rolls, and the corrugations 30 are allowed for by the extension of the scored sections so that the width of the corrugated sheet is substantially the same as before. The corrugated sheet is then subjected to the action of spreading mechanism 35 which increases the width of the sheet and produces the finished product of a thickness substantially equal to twice the width of the strands of the scored sheet. The non-scored portions of the sheet may also be 40 submitted to transverse or longitudinal corrugation depending upon the mechanism employed or the character of the product desired.

Figure 1, is a diagrammatic view of a 50 train of rolls for carrying out the process in one way. Fig. 2, is a diagrammatic view of a train of rolls and punches for carrying out the process in another way. Fig. 3, is a fragment of a sheet showing the arrangement of the scoring according to my invention. Fig. 4, is a diagrammatic view of a

fragment of a finished product made according to my improved method with transversely corrugated longitudinal strips. Fig. 4^a is a similar view of a fabric with a 60 flat border strip. Fig. 5, is a fragmentary sectional view showing dies for bending over the edges of the sheet. Fig. 6, is a fragmentary sectional view showing dies for longitudinally corrugating a scored 65 sheet. Fig. 7, shows a pair of grooved rolls such as may be used for longitudinally corrugating the scored sheet or for feeding the longitudinally corrugated stock. Figs. 8, 9 and 10 show rolls for performing successive steps in spreading the fabric. Fig. 11, is a diagrammatic sectional view of fabric made according to my invention and showing longitudinally corrugated ribs.

The sheet is scored by suitable cutters, 75 punches or dies so as to consist of three or more longitudinal strips 1, 1, and extensible sections 2, 2. The scoring may be by cutting the metal either with or without removing metal or by indenting the metal so 80 that it is weakened along the desired lines and thus made susceptible to fracture in a subsequent rolling or corrugating operation. The scoring is along lines diagonal relative to the length of the sheet and each section 85 is made up of two scored portions 3 and 4, the lines of which converge toward the center 5 of the section. There are a number of slits or score marks in each of the rows so as to form diagonally arranged strands 6 90 and 7 with adjacent strands connected to each other at a plurality of points such as 8, 9 and 10. The strips 1, 1, 1, may be made of any desirable width depending upon the character of product desired. 95 The score marks of the two portions 3 and 4 may approach each other along the center line 5 as near as desired. In the arrangement shown in Fig. 3 there is a continuous strip of metal 5 connecting the scored portion 3 and the scored portion 4 but the score marks of the two portions may be connected so as to entirely interrupt the continuity of the strip 5 as indicated for instance, by the cross connecting mark 5' in 105 the scored section, Fig. 3.

In Fig. 1, the rolls 11 are for feeding the blank stock. The rolls 12 are for slitting or otherwise scoring according to the arrangement shown in Fig. 3. The rolls 13 110 are for feeding the stock away from the scoring rolls and may be so adjusted as to

smooth the scored stock and remove bur formed by the scoring operation. The rolls 14 are for bending over the edges of the sheet so that it may be more readily fed 5 through the longitudinal corrugating rolls 15 and 16. The scored stock is fed in the direction of the arrows of Figs. 1, 2 and 3. By forming the longitudinal corrugations gradually a more uniform action can be attained. The longitudinal corrugating action 10 bends the strands 6 and 7 and opens out the meshes as indicated in Fig. 6. Rolls such as 17 may be used to feed the metal and form transverse corrugations (Fig. 4) in the un-scored portions 1, 1. These transverse corrugations compensate for the tendency of the scored portion to decrease in length in the longitudinal corrugating action of the sheet and prevent distortion even 15 though the mechanism employed be of light weight. The connecting portion 5 tends to travel backward relative to the strips 1, 1, and the uniform corrugation action is facilitated by assisting in this relative longitudinal movement. The longitudinally corrugated product, of the original width of the sheet but of a thickness determined by the depth of the longitudinal corrugations, is then spread out for instance, by 20 being fed through a number of pairs of rolls such as 18, 19, 20 and 21 which gradually spread the sheet without closing up the meshes formed in the longitudinal corrugating action. The sheet is then fed out by 25 means of one or more pairs of rolls such as 22 (and 23 Fig. 2) which serves to set the strands and prevent the sheet from buckling.

In the arrangement shown in Fig. 2 the 30 scoring is accomplished by slitting dies 121, one member of which is reciprocable. The edge bending is accomplished by dies 141 and the longitudinal corrugation is effected by dies 151 one of which is reciprocable, 35 preferably the upper. By inclining the lower edge of the upper die 151 backward and upward from the front end, the corrugating action is accomplished gradually and therefore without danger of rupturing the 40 strands. By arranging transverse corrugating rolls such as 17 adjacent the longitudinal corrugating dies 151, the unslitted portions can be fore-shortened to correspond with the fore-shortening of the slitted portions in the longitudinal corrugating action 45 of the sheet.

When the strip 5 is cross-scored as at 5' Fig. 3, the finished product may have small tangs such as 5" Fig. 4^a connecting the adjacent strands of the two scored portions 3 and 4 midway between the longitudinal strips 1, 1.

By employing suitable dies or rolls the longitudinal un-scored portions of the sheet 60 may be given longitudinal corrugations so

as to form channels or corrugated ribs such as 24 and 25 some of which, if desired, may be made to project substantially from the plane of the reticulated portion of the sheet.

The entire process may be carried out in 70 a single machine or preferably the scoring may be done on one machine and the corrugating and spreading in another—or the corrugating and spreading may be done in separate machines.

The formation of the channels or longitudinally corrugated ribs may be either before or after the scoring operation or during the longitudinal corrugating of the scored sections or before, during or after the spreading action. The formation of the channels may entirely compensate for the spreading out of the scored sections and in fact if the ribs are very deep the product may be of less width than the original blank sheet.

The right to claim the mechanism herein disclosed is reserved for other applications.

What I claim is:

1. The method of forming a reticulated product which consists in scoring a plurality of sections of a sheet along diagonal lines inclined toward the center of each section, then longitudinally corrugating the sheet so as to increase its thickness without decreasing its width and then spreading out 95 the corrugations laterally so as to increase the width of the sheet.

2. The method of forming a reticulated product which consists in scoring a section of a sheet along diagonal lines converging toward the center of the sheet and in staggered arrangement, feeding the sheet forward in the direction of convergence, subjecting the scored section to a longitudinal corrugating action to form meshes and then 105 flattening the sheet without closing the meshes.

3. The method of forming a reticulated product which consists in scoring a plurality of sections of a sheet along diagonal lines 110 inclined toward the center of each section, then longitudinally corrugating the sheet so as to increase its thickness and then successively and gradually bending the halves of the corrugated sections beginning at the 115 outer edge so as to flatten the sheet.

4. The method of forming a reticulated metal product which consists in scoring sections of a sheet, gradually feeding and corrugating the scored sections longitudinally 120 and then spreading out the corrugated sections.

5. The method of forming a reticulated metal product which consists in scoring sections of a sheet, gradually feeding and corrugating the scored sections longitudinally 125 and then gradually spreading out the corrugated sections.

6. The method of forming a reticulated metal product which consists in scoring sec- 130

tions of a sheet, corrugating the sheet longitudinally along the centers of the scored sections and along the unscored portions and spreading the corrugated sections.

5 7. The method of forming a reticulated metal product which consists in scoring sections of a sheet, corrugating the scored sections longitudinally, corrugating the unscored sections longitudinally and spread-

10 ing the scored sections laterally.

8. The method of forming a reticulated metal product which consists in scoring sections of a sheet, longitudinally corrugating the scored sections, transversely corrugating

the unscored sections and spreading out the 15 scored sections.

9. The method of forming a reticulated metal product which consists in scoring sections of a sheet, longitudinally feeding and corrugating the scored sections, feeding and 20 transversely corrugating the unscored sections and feeding and spreading out the scored sections.
